UNITED STATES PATENT OFFICE.

THOMAS E. NEW, OF CINCINNATI, OHIO, ASSIGNOR TO PRECISION EQUIPMENT COMPANY, OF CINCINNATI, OHIO, A CORPORATION OF KENTUCKY.

SPARK PLUG.

1,405,549.

Specification of Letters Patent.

Patented Feb. 7, 1922.

Application filed October 26, 1918. Serial No. 259,860.

To all whom it may concern:

Be it known that I, THOMAS E. NEW, a citizen of the United States, and a resident of Cincinnati, in the county of Hamilton and State of Ohio, have invented certain new and useful Improvements in a Spark Plug, of which the following is a specification.

This invention relates to internal combustion engines, and more particularly to spark plugs used in connection therewith, an object of the invention being to provide a spark plug which is designed so that the action of the piston of the engine with which the spark plug is used will prevent the accumulation of residue such as carbon, oil or the like, upon the electrodes or sparking points of the plug.

More specifically, an object of this invention is to provide a spark plug including a central stem provided with a longitudinally extending bore, the lower end of which stem forms one of the electrodes or sparking points of the spark plug, while the other electrode is shaped to have its sparking point or end positioned adjacent to the lower end of the stem, whereby the inrush of air through the longitudinal bore of the stem, upon the suction stroke of the piston of the engine upon which the spark plug is used, will blow carbon, oil or other residue from the sparking ends of the two electrodes, and prevent the consequent fouling of the spark plug.

Another object of the invention is to provide a spark plug as specified, wherein a valve structure is provided and arranged to automatically seat itself upon the compression stroke of the piston of the engine, to prevent the escape of combustible gases through the bore of the stem of the spark plug; also to provide adjustable means for regulating the amplitude of movement of the valve for varying the amount of air admitted to the cylinders so as to provide the proper mixture in each cylinder, which air entering the cylinder mixes with the gas therein, and tends to save gasoline or the volatile fuel used in the engine.

Other objects of the invention will appear in the following detailed description, taken in connection with the accompanying drawing, forming a part of this specification, and in which drawing:

Figure 1 is a side elevation of the improved spark plug, and

Figure 2 is a longitudinal section through the spark plug taken at right angles through Figure 1.

Referring more particularly to the drawing, 1 indicates the shell of the spark plug, 60 which is of the usual construction being threaded, as shown at 2, for connection with the head of an ordinary internal combustion engine, and having an electrode 3 carried thereby. The shell 1 carries the usual porcelain or insulating sleeve 4, through the center of which a stem 5 extends. The lower end of the stem 5 projects beyond the lower end of the porcelain sleeve 4, and also below the lower end of the shell 2, coacting with the 70 electrode 3, in forming the sparking point of the spark plug. The stem 5 is threaded, a short distance upwardly of its lower end, as shown at 6, which threaded portion engages in the washer 7 which abuts the lower end 75 of the porcelain sleeve 4. The stem 5 is provided with a longitudinal bore 8, extending throughout its entire length, which bore communicates, at the upper end of the stem, with a duct 9 formed in the removable head 10 of the spark plug. As shown in the drawings, this removable head 10 is formed of suitable conducting material, and is substantially hexagonal in shape, presenting a flat edge surface which engages against 85 a washer 11 mounted upon the upper end of the porcelain sleeve 4. The stem 5 is threaded into the head 10 for connecting the head to the main body of the spark plug.

The duct 9 which communicates with the 90 bore 8 of the stem 5 also has communication with an opening or recess 12 formed in the head and this recess or bore opens out through one of the flat faces of the head 10, having its outer portion threaded for receiving therein a set screw 13. The set screw 13 has a stem 14 formed upon its inner end which is adapted for engagement with the ball valve 15 which is seated in the recess 12. The ball valve 15 is adapted to cut off communication between the recess 12 and the relatively short passageway 16 which communicates with the inner end of the recess 12 and with a transverse way 17. The transverse way 17 opens out into a counter sink 105 or cup 18 formed in one of the upwardly facing sides of the head 10 as clearly shown in Figure 2 of the drawing, so as to permit the entrance of air through the cup 18, ways 17 and 16 into the recess 12 and from this 110

recess into the duct or way 9 and downwardly through the bore 8 of the stem 5 upon the suction stroke of the piston of the engine with which the spark plug is associated, for causing a blast of air about the spaced sparking point of the plug to flow residue, such as carbon, oil or the like from these sparking points and consequently prevent the fouling of the sparking points of the plug. This air passing through the bore 8 of the stem 5 also mixes with the combustible fuel in the cylinder of the engine, tending to require a smaller amount of volatile or combustible fuel than is ordinarily the case in internal combustion engines, and consequently resulting in economizing or saving of gasoline, or analogous fuel.

The adjustment of the set screws 13 regulates the amplitude of movement of the ball valve 15 and consequently regulates the quantity of air admitted to the cylinder through the bore 8. A locking nut 19 is mounted upon the set screw 13 for holding this set screw against accidental adjusted movement.

A binding screw structure 20 is carried by the head 10 for permitting the connection of an electric conducting wire thereto.

It is evident that if it is so desired gasoline or other suitable volatile liquid may be introduced into the cylinder of the engine, through the spark plug, by placing a small quantity of the said volatile fluid in the cup 18.

Changes in details may be made without departing from the spirit of this invention, but;

I claim:

1. In a spark plug, the combination of a body portion having a hollow stem extending therethrough, a head block, provided with angularly disposed sides adapted to seat at one side upon the upper end of the body portion and having a threaded aperture at said side for the reception of the upper end of said stem for detachably securing the head block to the body of the plug, said block having a downwardly inclined recess therein opening through one of the upwardly facing sides and provided with a valve seat in its lower end and a passage leading from the recess at a point above the valve seat com-

municating with said stem, a removable plug fitted through said upwardly facing side for closing said recess, a valve in said recess adapted to engage said valve seat and said plug being adapted for adjustment in the recess to limit the movement of the valve, said head block further having a lateral opening leading from beneath said valve seat upwardly through a second upwardly facing side through which air is adapted to be fed to said stem through said recess when the valve is opened.

2. In a spark plug, the combination of a body part having a hollow stem extending therethrough and screw threaded at its upper end, a head detachably fitting upon the upper end of the body and provided with an opening threaded to receive the upper end of the stem and for communication with the stem, said head having a downwardly inclined recess therein opening through the upper face of the head and terminating in a valve seat at a point below said passage in the head and communicating with said passage, a plug fitting in said upper side of the head for adjustment in the recess, a valve in the recess adapted to normally engage said seat for closing the passage through the head, said head having an intake opening leading from the upper side of the head to a point beneath said valve seat and adapted to admit air through the head, and a terminal connection carried upon the upper end of the head and having electrical connection with said stem whereby a terminal wire may be attached to the spark plug without removing said head.

3. A spark plug having in combination a central electrode having a longitudinal passage therein; a valve cap positioned upon the terminal end of said electrode and having a passage therein, said passage extending downwardly and in angular relation with said longitudinal passage and communicating therewith and with the atmosphere, a ball valve seated in said downwardly extending passage and controlling the communication with the atmosphere, and adjustable means secured to the upper portion of said passage for limiting the upward movement of the ball in the passage.

THOMAS E. NEW.
